STACKER MECHANISM

Thomas B. Dalton, Montague, Mich., assignor, by
mesne assignments, to Valley Research Corporation,
Montague, Mich., a corporation of
Michigan

Application March 21, 1950, Serial No. 150,867

14 Claims. (Cl. 53—34)

1

This invention relates to a stacker mechanism for stacking products preparatory to such products being wrapped in a wrapping machine, the present mechanism being particularly designed for the stacking of prints of butter or oleomargarine so that they can be wrapped in a wrapping machine of any suitable kind such as those disclosed in my copending applications, Serial No. 29,435, filed May 27, 1948, and Serial No. 121,857, filed October 17, 1949.

One object of the present invention is to provide a stacking machine which is operable as a unit including its own motor for operation of its mechanism, such mechanism being so designed and so connected with a wrapping machine that it is timed by a cyclically operable element of the wrapping machine so as to deliver a stack of products to the machine, one each cycle of its operation and at the proper time in that cycle.

Another object is to provide a stacker mechanism for stacking prints of butter, oleomargarine or the like delivered to the mechanism in a single layer so that the product is discharged from the stacker mechanism with any desired number of prints in a stack depending on the design of the machine, the present disclosure being for four quarter-pound prints of the product which prints are square in cross section, or two half-pound prints which are rectangular in cross section (each print in the latter case being the same size in cross section as two quarter-pound prints).

Still another object is to provide an elevator for elevating two quarter-pound or one half-pound print from a delivered position on an intake conveyor to a position on an elevator for moving the product to an elevated position, means being provided to support the product at the elevated position whereupon two more quarter-pounds or one half-pound of the product is elevated thereunder to raise the same and thus provide a stack of four quarter-pounds or two half-pound prints, the elevator operating twice during a cycle of operation of the stacker mechanism.

A further object is to provide a pusher plate operable to push the stacked product from its elevated and supported position on to an outlet platform, the pusher plate being operable at half the speed of the elevator so as to operate once each cycle of operation of the stacker mechanism, a novel and simple mechanical drive for the pusher plate being provided which, through a crank drive for the pusher plate and associated mechanism, elevates the pusher plate over the next stack of articles being stacked.

2

Still a further object is to provide a clutch interposed between a motor for operating the stacker mechanism and the elevator and pusher plate actuating mechanisms to start the operation of the machine when the product is delivered by the intake belt conveyor to the elevator.

An additional object is to provide a timing connection between the wrapping machine receiving the product from the stacker mechanism and the drive for the stacker mechanism which times the stacker mechanism with the wrapping machine by stopping the stacker machine each cycle of the wrapping machine, the wrapping machine being driven at a slightly higher speed than necessary for this purpose and having a timing latch to stop the mechanism while the motor continues to operate, a friction clutch connection being provided between the motor and the stacker mechanism to permit such stopping and the wrapping machine once each cycle of operation thereof operating the timing latch for permitting the stacker mechanism to start operating at the proper time in each cycle of operation of the wrapping machine.

With these and other objects in view, my invention consists in the construction, arrangement and combination of the various parts of my stacker mechanism, whereby the objects contemplated are attained, as hereinafter more fully set forth, pointed out in my claims and illustrated in the accompanying drawings, wherein:

Figure 1 is a side elevation of a stacker mechanism embodying my present invention.

Figure 1^a is a view of a portion of the wrapping machine shown in my first above mentioned copending application illustrating a timing connection between it and the stacker mechanism of Figure 1, Figure 1^a being a continuation of the right hand end of Figure 1.

Figure 2 is a rear elevation of Figure 1, that is, looking at the intake end of the stacker mechanism which is the left hand end in Figure 1.

Figure 3 is a vertical sectional view on the line 3—3 of Figure 1 to illustrate more clearly some of the details shown in Figure 2.

Figure 4 is a vertical sectional view on the line 4—4 of Figure 2.

Figure 5 is an enlarged vertical sectional view on the line 5—5 of Figure 4 to illustrate a friction clutch connection between a gear box and the stacker mechanism.

Figure 6 is a vertical sectional view on the line 6—6 of Figure 2.

Figure 7 is a vertical sectional view on the line 7—7 of Figure 2 showing details of the pusher plate.

3

Figure 8 is a vertical sectional view on the line 8—8 of Figure 6.

Figure 9 is a view similar to a portion of Figure 6 at its right hand end showing the parts in a different position.

Figure 10 is an elevation of an elevator latch plate per se.

Figure 11 is an enlarged sectional view on the line 11—11 of Figure 6 showing the lower end of the elevator latch plate in cross section and its cooperation with an elevator guide.

Figure 12 is an enlarged vertical sectional view on the line 12—12 of Figure 3 showing a timing latch mechanism and a clutch mechanism of the machine.

Figure 13 is a vertical sectional view on the line 13—13 of Figure 12 showing details of the clutch mechanism.

Figure 14 is an enlarged elevation of a portion of Figure 1, the line 14—14 of Figure 3 indicating where the view is taken.

Figure 15 is an enlarged vertical sectional view on the lines 15—15 of Figure 3 showing the timing gear connections between an elevator operating shaft and a pusher plate operating shaft of the mechanism; and

Figure 16, 17, 18 and 19 are diagrammatic views showing various positions of the main elements of the stacker mechanism in four steps during a cycle of operation thereof, dotted positions therein showing positions of the parts intermediate such steps.

On the accompanying drawings I have used the reference numeral 20 to indicate a main frame on which the mechanism of my stacker is mounted, the frame itself being leg supported and the legs being indicated at 21. An intake conveyor belt 22 is provided which passes around a driving drum 23 and an idler drum 24. These drums are mounted on shafts 25 and 26 supported by bearings 27 and 28.

The belt 22 is supported by a plate 29 between conveyor sides 146. The plate 29 is supported on a cross bar 30 and is adapted to deliver the product which will be referred to hereinafter as a "print" P to an elevator 31. The elevator consists of two L-shaped plates, the horizontal legs of which are designated by the reference numeral 31 already referred to and the vertical legs 129 of which constitute aprons. For all practical purposes the two elements 31 constitute a single elevator member which will hereinafter be referred to as "elevator 31." The elevator 31 is adapted to receive the prints prints P after the elevator is raised from the lowered position of Figure 9 and elevate them to the raised position of Figure 6, the aprons 129 at that time preventing overfeeding of the prints P on the intake conveyor belt 22 while the elevator is in the upper position.

A pusher plate 32 is adapted to push a stack of four of the prints P from the elevator and on to an outlet platform 33. The platform 33 is supported by a cross bar 34 which in turn is supported on posts 35 extending upwardly from the frame 20 and connected together at the top by a cross-bar 36. The cross-bar 30 is supported by posts 37 and the posts 35 and 37 are connected together on the near side in Figure 1 by a slide bar 38 and on the far side by a tie bar 39 (see Figure 2).

The mechanism for accomplishing the stacking of the prints as just described in a general way will now be described in detail. The shaft 25 which constitutes a drive shaft for the conveyor

belt 22 is driven by a chain 40 (see Figure 4). The chain meshes with a sprocket 41 on the shaft 25 and a sprocket 42 on a shaft 43. The shaft 43 is the low-speed shaft of a gear reducer shown generally at 44 in Figure 1 and having a high-speed shaft 45 provided with a pulley 46. A belt 49 extends around the pulley 46 and around a pulley 50 which is mounted on a motor shaft 51 of a motor 52. The motor is suitably supported on the frame 20 as illustrated.

In Figure 5 I illustrate a friction drive between a low-speed gear reducer shaft 43 and the sprocket 42. This consists of a sleeve 53 secured to the shaft as by a pin 54 and having mounted on it a cup-like collar 55 and a friction disc 56. The collar is secured to the sleeve by the pin 54 and a set screw 57 secures the disc 56 to the sleeve. A second friction disc 58 floats on the sleeve and the sprocket is floatingly mounted between the two discs. A spring 59 is interposed between the disc 58 and the collar 55 to provide the necessary friction for driving the sprocket 42 from the shaft 43, the spring, of course, being of the proper tension for permitting slip after a predetermined degree of torque on the shaft 43 after the sprocket 42 is stopped by a timing latch as will herein-after appear.

An elevator crank shaft 60 is provided (see Figures 2 and 3) and it is journaled in upright frame members 61 and 62. A crank 63 is mounted thereon and the crank has a crank pin 64 connected by a link 75 with a pin 66 extending from a slide 67. The slide 67 encircles a slide bar 68 and is provided with an angle-shaped bracket having a vertical leg 69 and the horizontal length 70 as also shown in Figure 8. Posts 71 extend upwardly from the leg 70 and connect with the elevator elements 31 as shown in Figure 9. The slide bar 68 is stationarily mounted at the lower end on the post 35 and at its upper end on the slide bar 38 as shown in Figures 1 and 4.

The elevator crank shaft 60 is driven from the shaft 25 by a chain 72. Meshing with the chain is a sprocket 73 on the shaft 25 and a sprocket 74 on the shaft 60. In Figures 3 and 13 the sprocket 74 is shown and in the latter figure it will be noted that it is secured by screws 76 to a collar 77 which is rotatably mounted on the shaft 60, a sleeve bearing 78 being positioned in the two. The collar 77 is rotatable relative to a second collar 79 which is pinned at 80 to the shaft 60.

Referring to Figure 12, the collar 79 is provided with a slot 81 adapted to receive the finger 82 of a clutch pawl 83 which is pivoted at 84 to the collar 77. A leaf spring 85 tends to engage the finger 82 with the slot 81, the spring being secured to the collar 77 by a screw 86.

A clutch control dog 87 is pivoted at 88 and is provided with an extension 144 acting as a stop against a bracket 145 in which the pivot pin 88 and a rock shaft 91 are journaled. The dog 87 is normally rocked counter-clockwise to the position of Figure 12 by a light spring 147 and is kept in that position by a clutch control pawl 89 under the dog 87, a spring 95 normally tending to swing the pawl 89 to this position. The dog 87 is in the path of a lobe 90 on the clutch pawl 83 so as to swing the finger 82 of the pawl out of the notch 81 after the sprocket 74 rotates about three-fourths of a revolution, thus stopping the stacker because of no product to be stacked.

The rock shaft 91 on which the pawl 89 is mounted, as shown in Figures 6 and 9, is provided with a trip finger 92. This finger is adapted to be engaged by a print P¹ as illustrated in Figure 9

in order to swing the clutch control pawl 89 from the full line position to the dotted position of Figure 12 when the belt 22 delivers the product for stacking and the print P^1 reaches a stop plate 94. The finger 92 will then be in the position of Figure 6 and the dog 87 no longer locked in the raised position by the pawl 89 so that the spring 85 will cause the lobe 86 to depress the dog for permitting the pawl finger 82 to engage the periphery of the collar 79 so as to be forced by the spring 85 into the slot 81 when it comes around to a position of registry with the finger. Thus the stacker is started again whenever there are prints to wrap and each revolution of the sprocket 74 depresses the dog 87.

The prints P^1 , P^2 , etc. are driven by friction on the constantly traveling belt 22 which pushes print P^1 on to a supporting plate 93 and against the stop plate 94, the print P^1 (thus propelled by the belt 22) engaging and moving the finger 92 as above described. The stop plate 94 is actually a depending flange on the platform 33 as disclosed on the drawings.

The supporting plate 93 has two rectangular openings 140 therein and the elevator elements 31 and their aprons 129 travel upwardly through these openings. The elevator 31 elevates the prints between two elevator guide plates 96 supported by two bars 141 and 142 secured to the posts 35 and past a pair of elevator latch plates 97 also supported by the bars 141 and 142. These latch plates on their lower ends as shown in Figures 6, 10 and 11 are provided with supporting shoulders 98 for the prints to support them while the elevator is returning downwardly for additional prints in a manner which will be herein-after disclosed. The shoulders 98 also support the prints so that a stack of them may be pushed by the pusher plate 32 on to the outlet platform 33.

The pusher plate 32 is secured to brackets 99 as shown in Figures 6 and 7 which in turn are clamped to a rock shaft 100. The rock shaft is rotatably carried by brackets 101 which are mounted on a cross bar 102. The cross bar is carried at one end by a slide 103 as shown in Figures 1 and 4 which is slideable on the slide bar 38. Its other end is provided with a roller 130 which rolls along the tie bar 39. The elevation of the pusher plate 32 may be adjusted by the adjusting screw 104 shown in Figure 7, threaded in the bar 102 and engaging a stop arm 105 clamped to the shaft 100. Also clamped to the shaft 100 is an arm 106 carrying a roller 107, the purpose of which will hereinafter appear.

A pusher plate crank shaft 108 is journaled in the upright frame members 51 and 62 above the elevator crank shaft 60. The shaft 108 is geared to the shaft 60 by means of gears 109 and 110 shown per se in Figure 15. The gears 110 is secured directly to the shafts so that they rotate in synchronism, the shaft 108 at half the speed of the shaft 60.

The crank shaft 108 has a crank 111 thereon connected by a link 112 to a pin 113 carried by the slide 103. A finger 114 is secured to the link for cooperation with the roller 107 as will be described later. The stacker mechanism disclosed in this application is adapted for use in connection with a wrapping machine, the frame of which is indicated by the reference numeral 48 in Figures 1 and 4. This reference numeral, it will be noted, is underlined and likewise all underlined reference numerals throughout the drawings and particularly Figures 1, 1^a, and 4 are the same as 75 solid line positions being one-fourth of a cycle

those used in my copending application, Serial No. 29,435, filed May 27, 1948. The stacking machine of the present application is connected to the wrapping machine of the prior application by means of hooks 115 engaging studs 116 mounted on the frame members 48. The wrapping machine has an intake conveyor belt 47 for receiving the stacked prints of the product from the stacker machine of the present application.

Referring to the details of the wrapping machine as shown particularly in Figure 1^a, the frame member 48 extends forwardly and is connected with a frame member 10 as shown in the prior application and a rock shaft 134 is supported in relation to the frame member 10 as disclosed therein. The shaft 134 is oscillated once each cycle of the wrapping machine by a link 136 for swinging a pair of arms 131 having pins 132 to engage a pound of wrapped butter and move it from a pocket 65 of a multiple pocket rotor 17, the pounds of butter being wrapped at previous stations of the rotor 17. The rotor is advanced one pocket at a time in an intermittent fashion.

It is desirable to time the stacking machine of the present application with the wrapping machine to which it is attached and this is accomplished by providing a timing latch 117 in the form of an arm having a hook 118, the arm being pivoted at 119. The hook 118 is adapted to engage a timing arm 120 which is oscillatable on the pusher plate crank shaft 108 and connected to the gear 110 by a shock absorber spring 121. The spring is connected at one end to the gear and at the other end to the timing arm 120 by screws 122 and 123 respectively.

The timing latch 117 is connected by a link 124, a slide rod 125, a link 126 and an arm 127 to the rock shaft 134. A spring 128 normally tends to move the timing latch 117 to the dotted position of Figure 1 to engage the timing arm 120 and thus stop operation of the stacker mechanism as far back as the sprocket 42 in Figure 5, the shaft 43 then continuing to rotate with the discs 56 and 58 frictionally engaging and slipping over the opposite surfaces of the sprocket 42. At the proper time each cycle of operation the arm 127 moves clockwise far enough to disengage the hook 118 from the timing arm 120 (full line position in Figures 1 and 1^a) and thus permits the stacker mechanism to operate for another cycle. The relative speeds are such that the cycle of the stacker machine is completed slightly ahead of the cycle of the wrapping machine so that the timing arm 120 is engaged by the hook 118 to stop the operation of the stacker until the wrapping machine catches up with it and then permits the stacker to complete its next cycle, the cycles of course being repeated as long as the wrapping machine operates. When it ceases to operate, then the hook 118 will engage the timing arm 120 to prevent further operation of the stacker until the wrapping machine is again placed in operation.

The operation of the elevator 31 is such that it elevates two quarter-pound prints P during one rotation of the crank 63 and two more quarter-pound prints during a second revolution, all while the pusher plate crank 111 operates through one revolution. Thus, all four prints are pushed at one time off the elevator latch plates 97 and on to the outlet platform 33. Figures 16 to 19 illustrate the different positions of the main parts in diagrammatic manner, the solid line positions being one-fourth of a cycle

apart and the dotted lines showing intermediate positions of the parts.

In these four figures the link 75 is shown considerably shorter than its actual length in order to clarify the operation diagrammatically. Starting with the elevator 31 in the raised position as in Figures 1 and 6, the full-line position in Figure 16 corresponds thereto. It will be noted that the elevator 31 is at its upper limit of movement and the pusher plate has moved about one-fourth of the way forward. The intermediate position between Figures 16 and 17 is shown by dotted lines in Figure 16 and occurs when the machine has completed another one-eighth of a cycle and in this position the elevator 31 is substantially one-half the way down and is empty and the pusher plate 32 is one-half the way forward and moving prints P¹, P², P³ and P⁴ as illustrated by dotted lines.

In Figure 17 the crank 63 has reached the down position and prints P⁵ and P⁶ are pushed on to the supporting plate 93 by the belt 22 as soon as the elevator 31 and its apron 129 pass the upper surface of 93. The first four prints P¹, P², P³ and P⁴ elevated by the elevator 31 have been moved off the supporting shoulders 98 of the elevator latch plates 97 and are completely on the outlet platform 33. The crank 63 in the full-line position of Figure 17 is all the way down and in the dotted position is half way up. The elevator 31 accordingly is ready to engage the prints P⁵ and P⁶ and elevate them as in Figure 18. The down position in Figure 17 has a corresponding position for the pusher plate 32 which is one-fourth of the way forward and, in the dotted position of the crank 63, the crank 111 in its dotted position has moved the pusher plate 32 all the way forward.

In the next quarter of a cycle, the crank 63 moves the elevator 31 to its highest position as in Figure 18, solid lines, and the pusher plate 32 is moved one-fourth of the way back on the return stroke. At this time, the finger 114 is engaging the roller 107 because the link 112 is tilting upwardly with respect to the rock shaft 100 instead of downwardly. Accordingly, the pusher plate 32 is being lifted (arrow A) as well as slid backwardly so that it clears the prints P⁵ and P⁶ on the elevator 31. At the dotted position of the crank 63 the elevator 31 is half-way down and empty and the pusher plate 32 is half-way back and still lifted to clear the prints P⁵ and P⁶.

In the next quarter of a cycle as shown in Figure 19, the elevator reaches the down position whereupon prints P⁷ and P⁸ move on to the supporting plate 93 and the pusher plate 32 moves to a position three-fourths of the way back and at this time is lowering again (arrow B). Finally in the dotted position of the parts, the elevator 31 is halfway up and about ready to engage and elevate the prints P⁷ and P⁸ and the pusher plate 32 is all the way back.

The cycle is then repeated as shown in Figure 16 with the prints P⁷ and P⁸ engaging and elevating the prints P⁵ and P⁶ so that another stack of four prints will be in position to repeat the stacking cycle.

When the machine runs out of prints and the dog 87 and the pawl 89 are in the position of Figure 12, the shaft 60 will stop rotating when the lobe 90, depressed by the dog, lifts the finger 82 out of the notch 81. This stops both gears 109 and 110, consequently stopping the motion of both cranks 63 and 111. The weight of the cranks at

that time tends to rotate the machine in the reverse direction which would retract the lobe 90 from the dog 87 and allow the finger 82 to drop into the slot 81 which is undesirable. I accordingly provide a ratchet 137 clamped to the pusher plate crank shaft 108 as shown in Figure 14. A holding pawl 138 is pivoted to the upright frame member 61 and constrained by a spring 139 to engage the teeth of the ratchet 137 which are positioned so as to prevent such reverse rotation when the machine is stopped in the manner just described.

From the foregoing specification, it is obvious that I have provided a stacker mechanism which is comparatively simple as far as the number of parts required for operation is concerned. The design is such that the stacker may be an entirely separate unit operating under its own power, such unit being independent of the wrapping machine with which, however, it must cooperate to supply stacked products at the same rate that they are wrapped by the wrapping machine. An automatic timing connection is therefore provided which stops operation of the stacker when its cycle of operation has been completed which cycle is precalculated to be faster than the cycle of the wrapping machine itself. Accordingly, when the cycle of the wrapping machine is completed, it then releases the stacker so that it can commence its next cycle. Thus I am able to provide a separate stacker unit and yet synchronize it perfectly with the operation of the wrapping machine and this is all accomplished with a relatively simple arrangement that stalls the stacker mechanism without, however, stalling the motor and the gear reducer operated thereby, a friction clutch being provided to permit operation of this character.

The machine is also designed so that it will operate only when prints are supplied to it and providing the wrapping machine is operating. If there are no prints on the belt 22 the pawl 89 is then moved by the spring 95 to the full line position of Figure 12 to lock the dog 87.

As shown in Figure 9, the print P¹ engages the trip finger 92 to move the clutch control pawl 89 to a position where the clutch control dog 87 may be pushed by the lobe 90 out of the way, thus starting the stacker machine in operation if the timing latch 117 is in the solid line position of Figure 1. Thereafter the clutch control dog 87 is returned to the full line position of Figure 12 by the spring 147. As long as the pawl 89 is held in the dotted position of Figure 12 by a print against the finger 92, the dog will be allowed, due to the spring 147 being considerably weaker than the leaf spring 85, to move away from the lobe 90 but the moment there is no print to move the finger 92, then the pawl 89 will remain under the dog 87 to lock it in a position where it will engage the lobe 90 and retract the finger 82 from the notch 81 when the lobe rotates to a position of registry with the dog thus stopping the elevating mechanism and permitting only the belt 22 to operate. The introduction of additional prints on the belt 22 will then start the stacker to operating again when a print engages the trip finger 92.

Some changes may be made in the construction and arrangement of the parts of my stacker mechanism without departing from the real spirit and purpose of my invention. Accordingly, it is my intention to cover by my claims such modified forms of structure or use of mechanical equivalents as may be reasonably included within their scope. In said claims I have referred to the ele-

vator 31 elevating one unit of product and on a second stroke elevating a second unit and stacking it under the first unit. On the drawings I have shown two units elevated in the first stroke and two units in the second stroke. As the number of units is immaterial as long as one or more units are stacked under another one or more units, it is to be understood that the singular use of "unit" in the claims is also broad enough to cover more than one unit.

I claim as my invention:

1. In a stacker of the character described, a frame, a supporting plate and an outlet platform mounted thereon, an intake conveyor supported on said frame to deliver units of a product to said supporting plate, an elevator for engaging a unit delivered from said supporting plate and elevating the same, latch plates mounted on said frame above said supporting plate and receiving and supporting the unit elevated by said elevator, said elevator delivering an additional unit to said latch plates beneath the first unit, a pusher for engaging the two units and moving them off said latch plates and on to said outlet platform, an arm on which said pusher is mounted, said arm being pivoted, an elevator crank shaft and link mechanism for reciprocating said elevator, a pusher crank shaft and link mechanism for reciprocating said pusher, said crank shafts being geared together at a two-to-one ratio, and means for pivoting said arm and thereby elevating said pusher over the first unit supported by said latch plates during the return stroke of said pusher.

2. In a stacker mechanism, a frame, a supporting plate and an outlet platform mounted at different elevations thereon, an intake conveyor on said frame adapted to deliver units of a product to said supporting plate, an elevator for engaging a unit delivered from said supporting plate and elevating the same, means on said frame above said supporting plate for receiving and supporting the unit elevated by said elevator, said elevator delivering an additional unit to said means beneath the first unit, a pusher for engaging the two units and moving them off said means and on to said outlet platform, an elevator crank shaft and link mechanism for reciprocating said elevator, a pusher crank shaft and link mechanism for reciprocating said pusher plate, said crank shafts being geared together with said elevator crank shaft rotating at twice the speed of said pusher crank shaft, said pusher being swingably mounted for lifting over the first unit supported by said means during the return stroke of the pusher, said pusher and the link for said pusher having coacting arms to accomplish such lifting when the link is swung by the pusher crank to one side only of a line between the center of the pusher crank shaft and the pivot point of the link to the pusher.

3. In a stacker mechanism of the character described, a frame, a supporting plate and an outlet platform mounted thereon, an intake conveyor supported on said frame and adapted to deliver units of a product to said supporting plate, an elevator for engaging a unit delivered from said supporting plate and elevating the same on a first stroke thereof, latch plates mounted on said frame for receiving and supporting the unit elevated by said elevator, said elevator on a second stroke thereof delivering an additional unit to said latch plates beneath the first unit, a pusher plate for engaging the two units and moving them off said latch plates and on to said outlet platform, a first means for

reciprocating said elevator, a second means for reciprocating said pusher plate, said first and second means being geared together with said first means rotating at twice the speed of said second means, said pusher plate being swingably mounted for elevation over the first unit supported by said latch plates during the return stroke of the pusher plate, said pusher plate and said second means having coacting arms to accomplish such lifting.

4. In a stacker, a frame, a supporting plate and an outlet platform mounted thereon, an intake conveyor supported on said frame and adapted to deliver units of a product to said supporting plate, an elevator for engaging a unit delivered from said supporting plate and elevating the same, latch plates mounted on said frame above said supporting plate and receiving and supporting the unit elevated by said elevator on a first stroke thereof, said elevator on a second stroke delivering an additional unit to said latch plates beneath the first unit, a pusher plate for engaging the two units and moving them off said latch plates and on to said outlet platform, said stacker mechanism being adapted to deliver the stacked units to a cyclically operable wrapping machine and having a cycle of operation of slightly less length than the cycle of operation of the wrapping machine, and a timing connection with a cyclically operable element of the wrapping machine adapted to stall the stacker mechanism, the stacker mechanism having its own power source connected by a slip friction clutch with said stacker mechanism.

5. In a stacker mechanism of the character described, a frame, an outlet platform mounted thereon, an elevator, an intake conveyor adapted to deliver units of a product to said elevator, said elevator engaging a unit delivered thereto and elevating the same, latch plates mounted on said frame above said conveyor and receiving and supporting the unit elevated by said elevator, said elevator delivering an additional unit to said latch plates beneath the first unit, a pusher for engaging the two units and moving them off said latch plates and on to said outlet platform, said stacker mechanism being adapted to deliver the stacked units to a cyclically operable wrapping machine and having a cycle of operation of slightly less length than the cycle of operation of the wrapping machine, and a timing connection with a cyclically operable element of the wrapping machine adapted to stall the stacker mechanism at the completion of its cycle until the wrapping machine has completed its cycle.

6. In a stacker mechanism of the character described, a frame, a supporting plate and an outlet platform mounted thereon, an intake conveyor supported on said frame and adapted to deliver units of a product to said supporting plate, an elevator for engaging a unit delivered from said supporting plate and elevating the same, latch plates mounted on said frame above said supporting plate and receiving and supporting the unit elevated by said elevator, said elevator delivering an additional unit to said latch plates beneath the first unit, a pusher for engaging the two units and moving them off said latch plates and on to said outlet platform, power means for actuating said stacker mechanism, said stacker mechanism being adapted to deliver the stacked units to a cyclically operable wrapping machine and having a cycle of operation of slightly less length than the cycle of operation

11

of the wrapping machine, and a timing connection with a cyclically operable element of the wrapping machine adapted to stall said stacker mechanism, said stacker mechanism being connected by a slip friction clutch with said power means.

7. In a stacker mechanism of the character described, a frame, a supporting plate and an outlet platform mounted thereon, an intake conveyor supported on said frame and adapted to deliver units of a product to said supporting plate, an elevator for engaging a unit delivered from said supporting plate and elevating the same, means mounted on said frame above said supporting plate and receiving and supporting the unit elevated by said elevator, said elevator delivering an additional unit to said means beneath the first unit, a pusher for engaging the two units and moving them off said means and on to said outlet platform, an elevator crank shaft and link mechanism for reciprocating said elevator, a pusher crank shaft and link mechanism for reciprocating said pusher, said crank shafts being geared together at a two-to-one ratio, means for elevating said pusher over the first unit supported by said means during the return stroke of the pusher, said stacker mechanism being adapted to deliver the stacked units to a cyclically operable wrapping machine and having a cycle of operation of slightly less length than the cycle of operation of the wrapping machine, and a timing connection with a cyclically operable element of the wrapping machine adapted to stall said crank shafts, the stacker mechanism having its own power source connected by a slip friction clutch with said crank shafts.

8. In a stacker mechanism, a frame, an outlet platform mounted thereon, an elevator, an intake conveyor adapted to deliver units of a product to said elevator, latch plates for receiving and supporting a unit elevated by said elevator on a first stroke thereof, said elevator on a second stroke delivering an additional unit to said latch plates beneath the first unit, a pusher for engaging the two units and moving them off said latch plates and on to said outlet platform, an elevator crank shaft and link mechanism for reciprocating said elevator, a pusher crank shaft and link mechanism for reciprocating said pusher, means for elevating said pusher over the first unit supported by said latch plates during the return stroke of the pusher, said stacker mechanism being adapted to deliver the stacked units to a cyclically operable wrapping machine and having a cycle of operation of less length than the cycle of operation of the wrapping machine, and a timing connection with a cyclically operable element of the wrapping machine adapted to stall said crank shafts between the completion of the cycle of operation of the stacker mechanism and the completion of the cycle of operation of the wrapping machine.

9. In a stacker mechanism of the character described, a frame, a supporting plate and an outlet platform mounted thereon, an intake conveyor on said frame adapted to deliver units of a product to said supporting plate, an elevator for engaging a unit delivered from said supporting plate and elevating the same, latch plates mounted on said frame for receiving and supporting the unit elevated by said elevator, said elevator delivering an additional unit to said latch plates beneath the first unit, a pusher for engaging the two units and moving them off said

12

latch plates and on to said outlet platform, an elevator crank shaft and link mechanism for reciprocating said elevator, a pusher crank shaft and link mechanism for reciprocating said pusher, said crank shafts being geared together, said stacker mechanism being adapted to deliver the stacked units to a cyclically operable wrapping machine and having a cycle of operation of less length than the cycle of operation of the wrapping machine, and a timing connection with a cyclically operable element of the wrapping machine adapted to stall said crank shafts, the stacker mechanism having its own power source connected by slip friction means with said crank shafts and said intake conveyor.

10. In a stacker, a frame, an outlet platform mounted thereon, an elevator, an intake conveyor adapted to deliver units of a product to said elevator, latch plates receiving and supporting a unit elevated by said elevator, said elevator delivering a second unit to said latch plates beneath the first unit, a pusher for engaging the two units and moving them off said latch plates and on to said outlet platform, said stacker mechanism being adapted to deliver the stacked units to a cyclically operable wrapping machine and having a cycle of operation of slightly less length than the cycle of operation of the wrapping machine, and a timing connection with a cyclically operable element of the wrapping machine adapted to stall said stacker each cycle of the wrapping machine, said stacker having its own power source connected by a slip friction clutch with said elevator, said pusher and said intake conveyor.

11. In a stacker mechanism of the character described, a frame, an outlet platform mounted thereon, an intake conveyor belt adapted to deliver units of a product, an elevator for engaging a unit delivered by said conveyor belt and elevating the same, latch plates receiving and supporting the unit elevated by said elevator, said elevator on delivering an additional unit to said latch plates beneath the first unit for thereby stacking the two units, a pusher for engaging the stacked units and moving them off said latch plates and on to said outlet platform, an elevator crank shaft and link mechanism for reciprocating said elevator, a pusher crank shaft and link mechanism for reciprocating said pusher, said stacker mechanism being adapted to deliver the stacked units to a cyclically operable wrapping machine and having a cycle of operation of less length than the cycle of operation of the wrapping machine, and a timing connection between a cyclically operable element of the wrapping machine and said crank shafts, the stacker mechanism having its own power source connected by a slip friction clutch with said crank shafts and said intake conveyor belt.

12. In a stacker mechanism, a frame, a supporting plate and an outlet platform mounted thereon, an intake conveyor supported on said frame and adapted to deliver units of a product to said supporting plate, an elevator for engaging a unit delivered from said supporting plate and elevating the same, means mounted on said frame for receiving and supporting the unit elevated by said elevator, said elevator on a second stroke delivering an additional unit to said means beneath the first unit, a pusher for engaging the two units and moving them off said means and on to said outlet platform, said stacker mechanism being adapted to deliver the stacked units to a cyclically operable wrapping machine and having a

cycle of operation of less length than the cycle of operation of the wrapping machine, a timing connection with a cyclically operable element of the wrapping machine adapted to stall the stacker mechanism, the stacker mechanism having its own power source connected by a slip friction clutch with the stacker mechanism, a clutch connection between said power source and said elevator and pusher including normally engaged elements, a clutch dog adapted to be positioned for disengaging said elements to thereby stop operation of the elevator and the pusher, and a trip finger and a clutch control pawl normally operable to retain said clutch dog in such position, said trip finger, when engaged by the product delivered by said conveyor belt on to said supporting plate, removing said clutch control pawl from coaction with said clutch dog.

13. In a stacker mechanism, a frame, an outlet platform mounted thereon, an elevator, an intake conveyor supported on said frame and adapted to deliver units of a product to said elevator for engaging a unit delivered by said conveyor and elevating the same, latch plates mounted on said frame above said supporting plate and receiving and supporting the unit elevated by said elevator, said elevator delivering an additional unit to said latch plates beneath the first unit, a pusher for engaging the two units and moving them off said latch plates and on to said outlet platform, said stacker mechanism being adapted to deliver the stacked units to a cyclically operable wrapping machine, and a timing connection with a cyclically operable element of the wrapping machine adapted to stall the stacker mechanism during a portion of each cycle of operation thereof, the stacker mechanism having its own power source connected by a slip friction clutch with the mechanism, a clutch connection between said power source, the mechanism and a trip finger operable to render said clutch connection operative when said trip finger is engaged by the product delivered by said conveyor to said elevator.

14. A stacker mechanism comprising a frame, 45

a supporting plate and an outlet platform mounted thereon, an intake conveyor supported on said frame and adapted to deliver units of a product to said supporting plate, an elevator for engaging a unit delivered from said supporting plate and elevating the same, means mounted on said frame above said supporting plate and receiving and supporting the unit elevated by said elevator, said elevator on a second stroke delivering an additional unit to said means beneath the first unit, a pusher for engaging the two units and moving them off said latch plates and on to said outlet platform, said stacker mechanism being adapted to deliver the stacked units to a cyclically operable wrapping machine and having a cycle of operation of slightly less length than the cycle of operation of the wrapping machine, a timing connection with a cyclically operable element of the wrapping machine adapted to stall the stacker mechanism between the completion of a stacker mechanism cycle and the completion of a wrapping machine cycle, and a clutch connection for said elevator and pusher including normally engaged elements, a clutch dog adapted to be positioned for disengaging said elements to thereby stop operation of the elevator and the pusher, and a trip finger normally operable to retain said clutch control dog in such position, said trip finger, when engaged by the product delivered by said conveyor on to said supporting plate, removing said pawl from coaction with said dog to permit operation of said clutch connection.

THOMAS B. DALTON.
